Dec. 518

William M. Snow of Providence, R. I.
Letters Patent No 518 Dated Nov. 2nd 1852

The schedule referred to in these Letters Patent and making part of the same

To all persons to whom these presents shall come:

Be it known that William M. Snow, of Providence in the County of Providence and State of Rhode Island, have produced a new and original design for the side plate of a cooking stove and hereby declare that the said new design is fully described and represented in the following specification, and accompanying drawings to which reference is hereinafter made.

The figures of the accompanying plates of drawings represent my new design. In Plate 1. Fig 1. is an elevation of the side plate. In Plate 2. Fig 2. is a section of the plate taken in the plane of the line A B, fig 1, and fig 3. is a view of the leg or support to the stove, forming one piece with the side plate.

The top of the plate is ornamented with the flat raised pieces a, a, and half bead moulding b, b, the base having on it the raised pieces c, c, &c. and bead work b, b. The sides are ornamented with the groins d, d, and circular drops e, e.

The upper small door is ornamented with mouldings f, f &c. and bead work b, b, and in the centre with the piece g raised on the sunken panel h, h, surrounded by the flat curved mouldings i, i. — The lower

Des. 518

small door h.h. is ornamented in a similar manner.

The oven door has around it mouldings f.f, bead work b.b, and flat mouldings i.i, enclosing a sunken panel l.l, on which is raised the square panel m.m, ornamented with studs n.n &c and in the centre with the raised shield o.o. The leg or support p.p. of the stove is of the shape shown in fig 3 Pl 2.

Having thus described my new design I shall state my claim as follows:-

What I claim as my new design and desire to have secured to me by Letters Patent is the new design consisting of the bead work, mouldings and ornamental configurations herein above described and represented in the drawings, for the side plate of a cooking stove.
